[57] CLAIM

The ornamental design for wrench for assembling hydrotherapy outlets, as shown and described.

DESCRIPTION

FIG. 1 is a perspective view of a wrench for assembling hydrotherapy outlets, showing my new design;

FIG. 2 is a front elevational view thereof;

FIG. 3 is a rear elevational view thereof;

FIG. 4 is a left side elevational view thereof, the right side being a mirror image;

FIG. 5 is a cross sectional view taken along 5—5 of

FIG. 1; and

FIG. 6 is a rear perspective view thereof.

FIG. 1

FIG. 4

FIG. 2

FIG. 3

FIG. 6

FIG. 5
